(57) **CLAIM**

The ornamental design for an operating panel as shown and described.

DESCRIPTION

FIG. 1 is an embodiment of an operating panel useable, for example, in or with a landing door of an elevator, illustrated in a first state.

FIG. 2 illustrates the operating panel of FIG. 1 in a second state.

FIG. 3 illustrates the operating panel of FIG. 1 in a third state.

FIG. 4 is another embodiment of an operating panel useable, for example, in or with a landing door of an elevator.

FIG. 5 is another embodiment of an operating panel useable, for example, in or with a landing door of an elevator.

FIG. 6 is a perspective view of another embodiment of an operating panel useable, for example, in or with a landing door of an elevator.

FIG. 7 is a perspective view of another embodiment of an operating panel useable, for example, in or with a landing door of an elevator; and,

FIG. 8 is another embodiment of an operating panel useable, for example, in an elevator car of an elevator.

Broken lines are used to illustrate features of the operating panel that form no part of the claimed design. Dash-dash broken lines are used to illustrate features of the operating panel that form no part of the claimed design. Dot-dash-dot broken lines are used to illustrate a boundary and form no part of the claimed design. Transitions between the different states of FIGS. 1-3 are unclaimed.

1 Claim, 8 Drawing Sheets
